UNITED STATES PATENT OFFICE.

JOSEPH W. BETTENDORF, OF BETTENDORF, IOWA.

JOURNAL-BOX LID.

Application filed March 23, 1927. Serial No. 177,654.

This invention relates to journal boxes and more particularly to lids therefor.

An object of this invention is to provide a journal box lid of the type having an integral pintle pin to cooperate with standard journal box hinge lugs and to provide such a lid with a spring having movable contact with the lid to apply yielding pressure against the outer face of the lid substantially at the center of the lid in order to insure a good bearing engagement between the lid and journal box entirely around the four sides of the lid.

Another object of this invention is to provide a removable journal box lid having an integral pintle with a spring which applies substantially equal pressure around the sides of the lid and which readily holds the lid in open and closed position.

A further object of the invention is to provide a journal box lid with an integral pintle pin which may be readily applied to or removed from a journal box and which lid can be readily removed together with the spring from the journal box.

A further object of the invention is to provide a mounting for a journal box lid with an integral pintle in which the lid can move freely toward the walls of the journal box to seat tightly thereagainst under pressure of the spring engaging the outer face of the lid.

Another object of my invention is to provide a rigid cover structure, or journal box lid, wherein a lid body portion, pintle, and connecting straps are associated together as a unit.

These and other objects will be apparent from the following description and annexed drawings, in which

Fig. 1 is a front elevation of a journal box with the lid in open position.

Fig. 2 is a section on line 2—2 of Fig. 1.

Fig. 3 is a front elevation of a journal box with the lid in closed position.

Fig. 4 is a side elevation of the journal box and lid as shown in Fig. 3.

Fig. 5 is a front elevation of the journal box with the lid removed.

Fig. 6 is a side elevation of the journal box with the lid removed.

Fig. 7 is a front elevation of the lid ready to be applied to the journal box; and

Fig. 8 is a side elevation of the lid.

The journal box 1 is of conventional construction and is provided with the hinge lug

2 having an eye portion 3 to receive the integral pintle 4 of the journal box lid 5. The lug is provided with suitable flattened portions 6 and 7 which are adapted to be engaged by the lid spring as will be more fully described.

The journal box lid 5 has the usual side flanges 8 to fit over the edges 1^a surrounding the mouth of the journal box and is provided with the integral pintle member 4 adjacent the upper marginal portion of the lid. The integral pintle member 4 is preferably offset from the body portion of the lid and is preferably formed by rolling a cylindrical portion of the metal forming the lid and bending back the wings 9 to overlie the offset connecting straps 10 which connect the pintle with the body of the lid. The wings 9 and connecting straps 10 together constitute a rigid connection between the pintle and the body portion of the lid and are preferably offset from the body portion in order that they may properly fit the standard hinge lug of a standard journal box. The body portion of the lid and straps 10 and pintle member 4 are thus associated together and function as a unit.

The ends of the hinge lug are preferably cut away to form reduced cylindrical portions 11 around which the curved end portions 12 of the spring 13 may be secured. Adjacent the center portion of the lid is a retaining strap 14 having its intermediate portion 15 secured to the lid and provided at its opposite ends with suitable raised flanges 16 to receive portions of the spring 13.

It will be noted that the side flanges 16 of the retaining strap 14 loosely engage the spring so that the spring may move relative to the body of the lid.

The spring 13 is preferably formed from a wire and comprises the curved end portions 12 which engage the reduced portions 11 of the hinge lug on the journal box and comprises the intermediate portions 17 which underlie the flanges 16 of the retaining strap 14. Between the portions 17 and the curved end portions 12 are formed humped portions 18 and the remainder of the spring comprises a looped end portion 19 bent upwardly to engage the flattened portions 6 and 7 of the hinge lug on the journal box.

The humped portions 18 of the spring are

provided to permit the ends 12 of the spring to be pressed outwardly from the hinge lug of the journal box when the lid is swung to the position shown in Fig. 2 so that the end 5 portions of the spring may be forced outwardly so as to be out of longitudinal alignment with the hinge lug. The lid may then be moved bodily laterally through the eye portion of the hinge lug with the connecting 10 straps 10 and reinforcing wings 9 passing through the slot 22 of the hinge lug. Thus the lid may be applied to or removed from the journal box.

The body of the journal box lid may be 15 stiffened by suitable depressions 20 as is well understood, and the finger piece 21 may be provided for readily opening and closing the lid against the pressure of the spring 13.

By reason of the fact that the curved end 20 portions 12 of the spring are disposed behind the reduced portions 11 of the hinge lug and the looped end portion 19 of the spring engages the intermediate flattened portion of the hinge lug, the spring bears with considerable pressure upon the center of the lid. The eye portion 3 of the hinge lug is made of sufficient diameter to permit movement of the integral pintle of the lid transversely of the eye so that the upper portion of the lid 25 is free to seat itself against the upper edge 1^a of the journal box. It will thus be seen that the outward pressure on the spring is substantially entirely taken by the hinge lug of the journal box and that the lid is 30 free to seat itself around the journal box by reason of the fact that the spring pressure is applied to the outer face of the lid and substantially at the center.

It will be seen that as the lid is moved to 40 open or closed position relative movement may occur between the lid and spring, thus insuring the spring following the lid in its movement to open or closed position. It may also be noted that with my construction permitting movement of the lid transversely of the hinge lug, the seating of the lid tightly 45 against the four sides 1^a of the journal box is insured.

It will furthermore be noted that I have 50 provided an advantageous unitary cover structure for a journal box, in which a lid body portion and pintle and connecting straps are associated together and operate as a unit.

55 It will also be seen that with this construction I have provided a simple and efficient journal box lid which is provided with an integral pintle and which may be readily applied to or removed from a standard journal box hinge lug.

It will also be seen that I have provided a journal box lid which is rigid in construction and which does away with any danger of losing loose hinge pintles, cotter pins and 65 the like and which lid, together with the

pintle, may be readily formed from a single plate of metal.

Furthermore, it is to be understood that the particular forms of apparatus shown and described, and the particular procedure set forth, are presented for purposes of explanation and illustration and that various modifications of said apparatus and procedure can be made without departing from my invention as defined in the appended claims. 75

What I claim is:

1. The combination with a journal box provided with a hinge lug, of a journal box lid having a body portion and an integral pintle connected therewith by integral connecting straps at the sides of the upper margin of the lid, said pintle being pivotally mounted in said lug, and a spring member having curved end portions mounted for rotatable movement on the lug, said spring having its intermediate portion secured to the outer face of the lid for slidable engagement therewith and having a looped portion to bear upon intermediate portions of the lug whereby substantially uniform pressure is exerted on the lid. 85

2. The combination with a journal box having a hinge lug provided with an eye, of a rigid unitary cover structure for the box having a lid body portion, and a pintle adapted to be inserted within the eye of the lug, a spring member having curved end portions rotatably mounted upon the ends of the hinge lug and having intermediate portions bearing upon the outer surface of the lid, another portion of said spring engaging the hinge lug to hold the lid in open or closed position, said intermediate portion of the spring being mounted on the lid for slidable engagement therewith, whereby substantially uniform pressure is exerted around the contacting portions of the lid and journal box when the lid is in closed position. 100

3. The combination with a journal box having a hinge lug provided with an eye, of a lid for said box having an integral pintle adapted to be inserted within the eye portion of the lug, said pintle being of less diameter than the eye portion of the lug in order to permit the pintle to move bodily transversely of the lug, a spring member having curved end portions to rotatably engage the hinge lug and having intermediate portions slidably secured to the outer surface of the lid and having a looped portion to bear against the hinge lug, whereby substantially uniform pressure is exerted on the lid to cause it to seat tightly against the edges of the journal box. 115

4. The combination with a journal box having a hinge lug provided with an eye portion and an outwardly opening slot, of a rigid unitary cover structure for said box having a lid body portion, and a pintle adapted to be inserted in the eye portion 130

of the hinge lug, a spring member having curved end portions to be rotatably mounted on the hinge lug, an intermediate portion secured to the outer surface of the lid for 5 slideable movement thereon, and a looped portion to bear against the hinge lug, said spring having portions between the curved end portions and the portions secured to the surface of the lid widely spaced from the 10 face of the lid, whereby when the lid is in open position the curved end portions of the spring may be pressed outwardly from the hinge lug of the journal box so that the lid may be bodily moved laterally through 15 the eye and slots of the hinge lug.

5. The combination with a journal box having a hinge lug provided with an eye portion, of a lid for said box having an integral pintle adapted to be inserted in the 20 eye portion of the hinge lug, said pintle being of less diameter than the eye portion of the lug, a spring member rotatably mounted on the hinge lug and having intermediate portions bearing against the outer 25 surface of the lid and a looped portion bearing against the lug intermediate the ends thereof, whereby the lid is pressed into tight engagement with the edges of the journal box around its entire line of contact there- 30 with.

6. The combination with a journal box having a hinge lug provided with an eye, of a lid for said box having an integral pintle adapted to be inserted within the eye portion 35 of the lug, said pintle being of less diameter than the eye portion of the lug in order to permit the pintle to move bodily transversely of the lug, and spring means carried by the lid and hinge lug bearing on the hinge lug and the outer surface of the lid for pressing the lid into tight engagement with the edges of the journal box around its entire line of contact therewith when the lid is in closed position 40

and to hold the lid in the desired open position. 45

7. The combination with a journal box provided with a hinge lug, of a rigid unitary cover structure having a lid body portion and a pintle spaced from said body portion 50 and straps extending from the sides of the upper margin of the lid to the pintle, said pintle being pivotally mounted in said hinge lug, and a spring member having curved end portions rotatably mounted upon the ends 55 of the hinge lug and having intermediate portions bearing upon the outer surface of the lid, another portion of said spring engaging the hinge lug to hold the lid in open or closed position, said intermediate portion 60 of the spring being mounted on the lid for slideable engagement therewith whereby substantially uniform pressure is exerted around the contacting portions of the lid and journal box when the lid is in closed position. 65

8. The combination with a journal box having a hinge lug provided with an eye portion, of a rigid unitary cover structure having a lid body portion and a pintle adapted to be mounted in the eye portion 70 of the hinge lug, said pintle being of less diameter than the eye portion of the lug in order to permit the pintle to move bodily transversely of the lug, and spring means carried by the lid and hinge lug and rotatably bearing on the periphery of the hinge lug and the outer surface of the lid for pressing the lid into tight engagement with the edges of the journal box around its entire 75 line of contact therewith when the lid is in closed position, and to hold the lid in the desired open position, said lug having an outwardly opening slot to permit mounting of the lid in operative position on the journal box. 80

85 In testimony whereof I affix my signature.

JOSEPH W. BETTENDORF.

Certificate of Correction.

Patent No. 1,648,254.

Granted November 8, 1927, to

JOSEPH W. BETTENDORF.

It is hereby certified that error appears in the printed specification of the above-numbered patent requiring correction as follows: Page 1, line 71, for the word "winds" read *wings*; and line 80, for the word "boy" read *body*; and that the said Letters Patent should be read with these corrections therein that the same may conform to the record of the case in the Patent Office.

Signed and sealed this 6th day of December, A. D. 1927.
